MEANS FOR UTILIZING EXHAUST STEAM

Johan Erik Johansson, Goteborg, Sweden, assignor to Aktiebolaget Götaverken, Goteborg, Sweden, a corporation of Sweden

Application November 17, 1933, Serial No. 698,512
In Sweden June 5, 1928

4 Claims. (Cl. 60—21)

This application is a continuation in part replacing my copending application Serial No. 383,132, filed August 2, 1929.

The present invention relates to means for utilizing exhaust steam of reciprocating steam engines and has for its general object the provision of means for transforming the available heat content of the exhaust steam into energy absorbed by the steam during expansion in the reciprocating steam engine. More particularly, the invention relates to steam power plants comprising a reciprocating steam engine, the exhaust steam of which is utilized in a steam turbine driving one or more pump devices in order to compress steam expanded in the reciprocating steam engine to a higher pressure, thus transforming the output of the exhaust steam turbine into heat energy absorbed by the steam in the reciprocating engine.

Still more particularly, the invention aims to provide combinations and arrangements of parts in such a manner that all of the cylinders of the reciprocating steam engine can be driven by superheated or at least drier steam than hitherto has been the case.

Another object of this invention is to provide means for increasing the smallest quantity of steam conveyed by the pump device per unit of time in order to obviate a steam flow through the pump device in a direction opposite to the intended one.

A further object of the invention consists in the provision of a pump device for the purposes set forth above, which under the greatly varying operation conditions can be driven with the highest possible efficiency.

A still further object of the invention is to provide means for bleeding steam from the reciprocating engine for heat exchanging purposes, said means being arranged so as to conduct, as far as possible, all moisture from the engine to the heat exchanging apparatus.

For a better understanding of the nature of the invention and the manner in which it is carried into effect, reference may be had to the accompanying drawings forming a part of this specification and the following description thereof.

In the drawings:

Fig. 1 is a plan view, partly in section, showing an embodiment of the invention;

Fig. 1a is a section taken on the line 1a—1a of Fig. 1.

Fig. 2 shows an indicator diagram;

Fig. 3 shows a modification of a detail of Fig. 1 in section.

Figs. 4 and 5 are diagrams illustrating the mode of operation of the turbo compressors used in the steam power plant according to the invention;

Fig. 6 is a modification of the steam power plant illustrated in Fig. 1;

Fig. 7 is a sectional view in an enlarged scale taken on the line VII—VII of Fig. 6; and

Figs. 8 and 9 are details of Fig. 7.

Referring now to Fig. 1, reference numeral 1 indicates a reciprocating steam engine arranged for triple expansion of steam in the cylinders 2, 3 and 4 thereof, high pressure steam being supplied from the steam generator 5 through the conduit 6 to the main stop valve 7 and, therefrom, to the piston valve 8. After expansion in the high pressure cylinder 2 the steam passes through the pipe 9, which serves as a receiver, into the distributing valve chest 10 and to the piston valve 11 and, therefrom, into the intermediate pressure cylinder 3. After having expanded therein, the steam is exhausted into the receiver 12 and then enters, by means of the slide valve 13, the low pressure cylinder 4 which exhausts the steam expanded therein into the exhaust steam pipe 14 connected with the condenser 15. The pipe 14 is further connected by means of a pipe 16 with an exhaust steam turbine 17 driven by steam finally expanded in the reciprocating engine 1. After having expanded in the exhaust turbine 17, the steam flows through a conduit 18 into the condenser 15.

The steam turbine 17 drives by means of a shaft 92, a low pressure turbo compressor 19 rotating at the same speed as the turbine. A gearing 20 connected with the turbine drives, by means of a shaft 93 partly lying below the shaft 92, a reciprocating high pressure compressor 21. The exhaust steam pipe 14 is also connected with a pipe 22 conducting steam to the suction side of the compressor 19. Stop valves 23, 24, and 25 are arranged in the pipes 14, 16, and 22, respectively. A container 26 located in the pipe 22 serves to equalize the difference between the quantity of steam flowing into the pipe 22 and the quantity of steam sucked in by the compressor 19 per unit of time. The pressure side of the compressor 19 is connected, by means of a pipe 27, with the receiver 12 at a point adjacent the slide valve 13. A pipe 28 connects the receiver 12 with the suction side of the compressor 21. The pressure pipe 29 of this compressor is connected with a superheater 30 arranged in the flue passage 31 of the boiler 5 and, by means of pipe 32, with the receiver pipe 9 at a point adjacent the piston valve 11. A by-pass pipe 44 having a

throttle valve 45 connects the pressure side of the turbocompressor with its suction side.

During normal operation, the stop valve 23 is in closed position whereas the valves 24 and 25 are opened so as to allow flow of steam from the exhaust pipe 14 to the steam turbine 17 and to the compressor 19. The steam sucked in by the compressor 19 is compressed to a pressure which is substantially equal to the pressure prevailing in the receiver 12, whereupon this steam, which has been superheated or at least dried by compression, is conducted through the pipe 27 to the said receiver for further expansion in the low pressure cylinder 4. It is obvious that the mixture of steam entering the low pressure cylinder will have a higher temperature or be drier than the steam exhausting from the intermediate pressure cylinder. Thus, the output of the low pressure cylinder will be increased materially and the low pressure cylinder will be fed with superheated or dry steam. In this manner, a portion of the output of the exhaust steam is rendered serviceable for the low pressure cylinder in the form of an increased quantity of steam of a higher temperature or at least having less moisture and a pressure suitable for utilization in this cylinder. The receivers 9 and 12 communicate in a similar manner with the high pressure compressor 21 by means of the conduits 28, 29, and 32. The steam taken out from the receiver 12 is compressed by the reciprocating compressor 21 to a pressure which is substantially equal to the pressure prevailing in the receiver 9. The compressed steam which has been superheated by compression is still more superheated in the superheater 30.

As will be seen from the drawings, the steam which has been compressed by the high pressure compressor is conducted back to the reciprocating engine at a point situated behind the high pressure cylinder, since the compression of steam up to the pressure prevailing in the live steam pipe would cause considerable difficulties. Therefore, I prefer to compress the steam to a pressure not higher than the pressure prevailing in the first receiver.

If it is desired to disconnect the turbine and the compressors, this may be effected by conducting the steam through the exhaust pipe 14 directly into the condenser 15. For this purpose, the valve 23 is opened and the valves 24 and 25 are closed.

In Fig. 1, I have also shown means for bleeding steam from the reciprocating steam engine, this steam being used for preheating of feed water. For this purpose, three feed water preheaters 33, 34, and 35 are connected to the reciprocating steam engine by means of pipes 36, 37 and 38 respectively. The feed water passes from the condenser 15 through the pipe 39 and the preheaters to the pump device 40 and, therefrom, into the boiler 5. The feed water preheater 33 is connected with the exhaust side of the valve chest of the low pressure cylinder so that a portion of the steam finally exhausted in the reciprocating engine is conducted to this preheater. The next preheater 34 is connected with the receiver 12. As the pressure side of the compressor 19 is connected with the same receiver, I have chosen such an arrangement of the pipes 27 and 37 that steam compressed by the compressor 19 is conducted into the receiver 12 at a point adjacent the slide valve 13 whereas the steam to be tapped off from this receiver is taken out at a point adjacent the piston valve 11. Because of the arrangement

thus provided superheated steam delivered from the compressor will tend to flow in a relatively short and direct path to the slide valve 13, whereas as the preheater 34, the inlet of which is adjacent the valve 11, will tend to draw off the relatively low quality steam discharged from the latter valve. With the arrangement illustrated, the natural path of flow of steam admitted to the receiver 12 from valve 11 and from the compressor discharge conduit 27 will tend to maintain a substantially higher quality of steam into the zone adjacent to the valve 13 than in the zone adjacent the inlet to the preheater. Consequently, the high temperature steam delivered from the compressor is substantially utilized in the succeeding cylinder of the engine and preheating is accomplished by steam of relatively low quality as exhausted to the receiver.

It is further to be noted that in view of the general flow of the steam through the receiver 20 from the valve 11 toward the valve 13, the relative positions of the inlet end of conduit 28 and the outlet end of conduit 27 leads to a natural tendency for conduit 28 to withdraw steam of lower rather than of higher quality from the receiver. If this latter steam contains moisture, such moisture will, as far as possible, be drawn off by the pipe 37. In the same manner, the steam compressed by the high pressure compressor 21 enters the receiver 9 at a point adjacent the piston valve 11, whereas the pipe 38 is connected with the receiver 9 at a point adjacent the outlet of the high pressure cylinder 2.

In order to reduce the dimensions of the compressors and the work of compression, the pressure of the steam supplied to the compressors should, if possible, be higher than the pressure prevailing in the cylinders during the exhaust period. This may be effected if the steam of a higher pressure exhausted from the cylinders during the exhaust lead period is supplied to the compressors, while the steam exhausted during the exhaust period is utilized for further expansion in the following cylinder or in the exhaust turbine respectively. Therefore, if according to Fig. 2 which illustrates, by way of example, the indicator diagram of the low pressure cylinder, p representing the pressure and v the volume of steam, the exhaust lead period begins at the point 41, an increased average pressure of the steam supplied to the compressor may be obtained.

For this purpose, the stop valve 25 in the conduit 22 may be replaced by a non-return valve opening in the direction to the suction side of the compressor. Fig. 3 shows this modified arrangement. As the steam quantity entering the pipe 14 during the exhaust lead period of the low pressure cylinder is materially greater than the steam quantity entering simultaneously the steam turbine 17, the pressure in the conduit 14 will increase. The non-return valve 42 then opens and the greatest portion of the steam exhausted during the exhaust lead period flows into the container 26. As during the exhaust period the pressure decreases in the conduit 14, the non-return valve closes and prevents the steam of higher pressure from flowing back to the conduit 14. The steam exhausted during the exhaust period will then flow to the steam turbine 17.

On account of the great variations of the flow of steam through the cylinders of the reciprocating steam engine and the great changes in the steam quantities conveyed to the compressors,

the compressors will work under peculiar operating conditions. I have found that, if the turbo compressor is constructed in the ordinary manner so as to normally give its maximum efficiency with the steam quantity conveyed per unit of time, the efficiency obtained will actually be considerably lower. I therefore, construct the turbo compressor so that its maximum efficiency occurs with a quantity of steam exceeding the average quantity conveyed per unit of time by at least 25 per cent. The operating conditions of the turbo compressor will be described more particularly in connection with Figs. 4 and 5.

Referring to Fig. 5, V represents the volume which, at a certain crank position of the reciprocating steam engine, flows through the compressor per unit of time. The line 46 indicates the changes in volume during one crank revolution and the line 47 represents the average volume V_m conveyed during said period. In the corresponding diagram in Fig. 4, the abscissae of the coordinate system represent the volume conveyed to the compressor and the ordinates thereof represent the efficiency of the compressor. Curve 48 indicates the changes of the pressure efficiency η with the volume V with a compressor intended to give its maximum efficiency at the average volume V_m , while curve 49 indicates the changes of the efficiency of a compressor which gives its maximum efficiency at a volume of 1.5 V_m . In a compressor operating with the changes of volume indicated by curve 46 and having an efficiency curve according to 48, an average efficiency is obtained which corresponds to the distance 51 indicated in the diagram, whereas the average efficiency of a compressor with an efficiency curve according to 49 reaches a considerably higher value represented by the distance 52. The upper ends of these two distances 51 and 52 are situated on a curve 50 on which a plurality of points may be calculated for compressors with other efficiency curves. After such a curve 50 has been plotted it will be possible to determine the average efficiency η_m under the conditions indicated for a compressor which is dimensioned so as to have its maximum efficiency at the volume corresponding to the point of the curve where the average efficiency is read off.

The curves 48 and 49, and corresponding curves for other volumes, have been obtained by tests with turbo compressors, and for the determination of curve 50 the following equation has been used:

$$\eta_m = \frac{\Sigma V t \eta}{V_m \Sigma t},$$

where t represents the time during which the volume V flows through the compressor. If Σt represents the time of one revolution of the reciprocating steam engine, this expression can be replaced by 360° , t being measured in degrees on the diagram in Fig. 5. For the calculation of η_m for a compressor having an efficiency curve according to curve 48, for example, the volume V is measured for a certain small angular displacement t° on the diagram in Fig. 5. With the value of V thus obtained the value of the corresponding η is measured on the curve 48. After the whole diagram 46 has been measured in this manner and multiplied by the corresponding η -values, $\Sigma V t \eta$ can be obtained and thus also

$$\eta_m = \frac{\Sigma V t \eta}{V_m 360}$$

Thereby a point has been determined on curve 50.

By a similar calculation for a plurality of other efficiency curves the determination of curve 50 has been effected.

It will appear from the form of this curve that it has its lowest value at small volumes, and that it reaches a maximum value at a volume of about 1.5 V_m , whereupon it slowly falls with greater V-values. Consequently, the compressor should be so constructed as to have its maximum efficiency at a volume of 1.5 V_m , it being possible, however, to permit variations of this volume between the limit values 1.25 V_m and 2.5 V_m without the average efficiency being materially lowered. By an overdimensioning of the compressor, which may be effected, for instance, by increasing the width of the channel areas of common turbo compressors, the additional advantage is obtained that the friction losses during the flow of steam through the compressor are reduced.

In Fig. 4 also a curve 53 has been shown, which indicates the pressure-increasing ability of the turbo-compressor at different values of the steam volume conveyed. It will be seen from the diagram that the pressures are remarkably low at small steam volumes, that is to say for the extent of the diagram denoted by 54—55. This circumstance is explained by the fact that a periodic flow of steam takes place through the compressor in a direction opposite to the intended one for said portion of the diagram. As the energy transferred by the compressor to the steam is substantially constant, the main portion of the energy is under such circumstances transformed into an increase in temperature of the steam. An increase in pressure as far as possible would be, however, more desirable, since this latter form of energy is easier to transform, by means of the reciprocating steam engine, into mechanical work. To ensure such an increase of the pressure, the turbo compressor 19 is by-passed by pipe 44 in which is inserted a throttle valve 45. By means of pipe 44 a portion of steam which has already been compressed is returned to the suction side of the compressor, in order thus to prevent the entrance of too small steam volumes conveyed by the compressor per unit of time. In Fig. 5, the diagram designated by 46 shows the variations of the volume conveyed by the compressor per unit of time if there is no return of steam from the pressure side to the suction side thereof, and the combination with curve 53 on Fig. 4 makes it clear that the pressures corresponding to the smallest volumes will fall on the portion of the pressure curve 53 extending between the points 54 and 55.

In consequence of the steam quantity which returns through the by-pass pipe 44 to the suction side of the compressor, a steam quantity corresponding to curve 56 indicated in Fig. 5 by chain-dotted lines will then flow through the compressor, so that all volumes corresponding to the portion 54—55 will be avoided. With the arrangement set forth, the compression in the compressor may thus be caused to develop exclusively according to the portion on the right of point 55 of the pressure curve 53 shown in Fig. 4, the best economical result being thus obtained, in that the energy supplied by the compressor is transformed as far as possible into an increase of the pressure of the steam.

In the modification shown in Figs. 6 to 9, the live steam enters the distributing valve chest 57 and, after having expanded in the high pressure cylinder 2, enters the receiver 58. The steam then flows through the intermediate and low

pressure cylinders 3 and 4, respectively, into the exhaust steam pipe 14, as described in connection with Fig. 1. The piston valve 11 of the intermediate pressure cylinder and the slide valve 13 of the low pressure cylinder are connected by means of a pipe 59 which serves as a part of the low pressure receiver 12. The exhaust steam turbine 17 drives two turbo compressors 19 and 60, respectively. The suction side of the low pressure compressor is connected to pipe 22 and its pressure side is connected, by means of pipe 27, with the low pressure receiver 59, 12. By means of the pipe 28, the high pressure compressor 60 sucks in steam from the receiver 59, 15 and the compressed steam is conducted through pipe 29, superheater 30, and pipe 32 into the receiver 58 at a point adjacent the piston valve 11 of the intermediate pressure cylinder 3. The pipe 37 for bleeding steam from the low pressure 20 receiver is connected to pipe 59 at a point adjacent the steam outlet chamber 61 of the intermediate pressure cylinder, while the pipe 38 through which steam of higher pressure is bled, is connected with the outlet chamber 62 of the 25 high pressure cylinder.

All of the parts indicated in Figs. 6 and 7 by the same reference numerals as in Figs. 1 and 3 serve the same purpose and operate in the same manner as the corresponding parts of Figs. 1 30 and 3.

While the low pressure compressor 19 is bypassed by a pipe 44 with a throttle valve 45 in the same manner and for the same purpose as in Fig. 1 the high pressure compressor 60 is bypassed by a pipe 63 connecting the receiver 58 with the receiver 59. The connecting pipe 63 is provided with a stop valve 64 and with a controlling device 65 which is shown on a larger scale in Fig. 9. The controlling device 65 comprises a cylinder 66 and a double piston 67 rigidly connected with the piston valve 11. The upper part of piston 67 and the cylinder 66 are provided with apertures 68 and 69, respectively, these apertures controlling the flow of steam from the receiver 58 45 through the pipe 63 to the receiver 59, depending on the position of the double piston 67 during each revolution of the reciprocating engine. The two parts of the double piston and the apertures are situated relatively to each other in such a 50 manner that a flow of steam through pipe 63 is possible only during those periods in the engine cycle when the steam quantity conveyed by the turbo compressor 60 tends to fall below the value indicated by the point 55 in the diagram of 55 Fig. 4. During such periods the controlling device 65 is opened by movement of the piston valve 11 so that, during these periods, a steam quantity according to the curves 70 in Fig. 5 will flow through the compressor 60 in order to prevent 60 the entrance of too small volumes conveyed by the compressor per unit of time. The arrangement of the controlling device is somewhat more complicated than the single throttling valve 45, but offers, on the other hand, the advantage that 65 an increase of the steam volume conveyed by the compressor takes place only during two short periods of each revolution of the reciprocating steam engine, thus decreasing the necessary amount of work required by the compressor.

70 In the modification according to Figs. 6 to 8, I have also shown an arrangement adapted to draw off steam from the low pressure cylinder 4 to the low pressure compressor 19 during the expansion in the cylinder, an exhausting means 75 being controlled so as to open at a point 43 (Fig.

2) before the beginning of the exhaust lead period represented at 41, whereby steam of a higher pressure is supplied to the suction conduit of the compressor. In this case, the pressure curve will sink somewhat as indicated in Fig. 2 5 by dash lines.

To effect this mode of operation, the cylinder covers 71 and 72 of the low pressure cylinder are provided with valves 73 and 74, respectively, connected with pipes 75 and 76, respectively, which 10 supply the steam drawn off from the cylinder to the container 26 and the compressor 19. The pipes 75 and 76 may be connected by a pipe 94. Under the influence of springs 77 and 78, the valves 73 and 74 are normally kept in closed position. The valve 73 is actuated by means of a lever 79 which is connected with a rod 80 guided by a bracket 81. The lower end of the rod 80 is provided with a roll 82 cooperating with a cam wheel 83. A spring 84 prevents disengagement of 15 the roll 82 and the cam wheel 83. The cam wheel is keyed on the crank shaft 85 and has an outwardly projecting cam 86 and, on the opposite side, a recess 87.

When the cam wheel is turned from the position shown in Fig. 8 in a counter-clockwise direction, the cam 86 will cause an upward movement of the rod 80 and a movement of the lever 79 about its fulcrum 88 in a clockwise direction, whereby the valve 73 is opened against the resistance of the spring 77. The cam 86 has such a position relatively to the crank 89 of the low pressure cylinder that the valve 73 begins to open at a point of the steam process corresponding to the point 43 in Fig. 2. The valve 74 on the other cylinder cover is actuated in a similar manner by means of the lever 90 likewise connected with the rod 80. When the recess 87 of the cam wheel is in a position below the roll 82, the rod 80 will be moved downwardly and the lever 90 turned in a counter-clockwise direction, thus opening the valve 74 against the resistance of the spring 78. By means of a hand lever 91, the cam wheel 83 is movable to a position indicated by 92, the valves 73 and 74 then being out of operation.

While in the foregoing description I have confined my consideration to a steam power plant comprising a triple expansion steam engine and two compressors, it will be understood that the invention is not confined to this specific arrangement but may equally well be embodied in steam power plants in which two or more cylinders are employed for expanding the steam down from boiler pressure to exhaust pressure and only one 55 compressor is provided for the compression of steam.

What I claim is:—

1. In a steam power plant, a reciprocating steam engine having a plurality of cylinders for multiple stage expansion of steam in the engine, said cylinders being double acting and the opposed ends of the same cylinder operating to expand steam through the same pressure range, means for admitting steam to and exhausting steam from each of said cylinders, a compressor, a turbine for driving said compressor, a conduit for conducting steam exhausted from one of said cylinders to the suction side of said compressor and a second conduit for conducting compressed steam from said compressor back to said engine for reexpansion therein, said compressor being constructed to operate with maximum efficiency when steam is supplied thereto at a rate equal to at least one and one-quarter times but not exceed- 75

ing two and one-half times the average rate at which steam is delivered by the engine.

2. In a steam power plant, a reciprocating engine having a plurality of cylinders for multiple stage expansion of steam in the engine, said cylinders being double acting and the opposed ends of the same cylinder operating to expand steam through the same pressure range, means for admitting steam to and exhausting steam from each of said cylinders, an exhaust steam turbine for expanding exhaust steam from said engine to a pressure lower than that to which the steam can be expanded in the engine, a compressor driven by said turbine, a conduit for conducting steam exhausted from one of said cylinders to the suction side of said compressor and a second conduit for conducting compressed steam from said compressor back to said engine for reexpansion therein, said compressor being constructed to operate with maximum efficiency when steam is supplied thereto at a rate equal to at least one and one-quarter times but not exceeding two and one-half times the average rate at which steam is delivered by the engine.

3. In a steam power plant, a reciprocating engine having a plurality of cylinders for serial expansion of steam therein, means for admitting steam to and exhausting steam from each of said cylinders, steam pumping means, a conduit for conducting steam exhausted from one of said cylinders other than the high pressure cylinder with the suction side of said pumping means, a

second conduit connecting said one of said cylinders with the suction side of said pumping means, valve means for controlling flow of steam through said second conduit, said valve means being opened and closed in accordance with the position of the crank shaft of said engine to permit steam to flow through said second conduit during a predetermined period of the engine cycle, and a third conduit for returning the steam delivered from said pumping means to said engine for further expansion therein.

4. In a steam power plant, a reciprocating engine having a plurality of cylinders for serial expansion of steam therein, means for admitting steam to and exhausting steam from each of said cylinders, a steam turbine, a conduit for conducting exhaust steam from said engine to said turbine, pumping means driven by said turbine, a second conduit for conducting exhaust steam from said engine to the suction side of said pumping means, a third conduit connecting the low pressure cylinder of said engine with the suction side of said pumping means, valve means for controlling flow of steam through said third conduit, said valve means being opened and closed in accordance with the position of the crank shaft of said engine to permit steam to flow through said third conduit during a predetermined period of the engine cycle, and a fourth conduit for returning steam delivered by said pumping means to said engine for further expansion therein.

JOHAN ERIK JOHANSSON.
